UNITED STATES PATENT OFFICE.

CARLETON ELLIS, OF MONTCLAIR, NEW JERSEY, ASSIGNOR TO RADIANT HEATING LIMITED, OF ARMLEY, LEEDS, ENGLAND, A CORPORATION OF GREAT BRITAIN.

PROCESS OF PRODUCING HEAT.

1,239,776.

Specification of Letters Patent. Patented Sept. 11, 1917.

Application filed December 6, 1911, Serial No. 664,304. Renewed February 9, 1917. Serial No. 147,723.

To all whom it may concern:

Be it known that I, CARLETON ELLIS, a citizen of the United States, and resident of Montclair, in the county of Essex and State of New Jersey, have invented certain new and useful Improvements in Processes of Producing Heat, of which the following is a specification.

This invention relates to processes of conducting combustion in furnaces or other heating appliances and relates in particular to processes involving the phenomena of surface combustion and the production of high radiative effects in furnaces, diaphragm bodies and the like; all as more fully herein-after described and as claimed.

The usual process of surface combustion involves injecting an explosive mixture of combustible gas and air into a mass of granular refractory material or other suitable porous and permeable bed of refractory material, at a speed greater than the speed of back firing of the mixture, so as to cause combustion to take place within the mass of granular material. If the gaseous combustible and air are preheated the speed of backfiring may become so high that an undue speed of travel of the explosive mixture, a speed which may even be prohibitive, is called for.

The process of the present invention involves the regulation and control of surface combustion under such circumstances in a predetermined manner, and comprises introducing into a porous mass or bed of refractory material a current of hot producer gas and a current of preheated air; positioning the loci of confluence, within the porosities of the mass of granular material, of the agents of combustion with respect to the pre-ignitive characteristics of the producer gas, the temperature of the preheated air, and the permeability of the porous mass; causing combustion to take place in said mass, whereby a predominating degree of surface combustion is secured and simultaneously the development of a maximum of radiant heat; absorbing the major portion of said radiant heat in the performance of useful heating operations; withdrawing the waste products of combustion; and regeneratively transferring a portion of the heat

of the latter to suitably preheat the combustible gas or air or both, or a portion of each, according to circumstances.

The conditions governing such an operation are as follows;—the various combustible gases used in industrial heating processes, such as natural gas, illuminating gas, water gas, hydrocarbon vapor gas, coke oven gas, Mond and producer gas, hydrogen, carbon monoxid, blast furnace gas, and the like, have, when mixed with a suitable amount of air or other supporter of combustion, differing rates of inflammation or explosive propagation which depend, essentially, on their pre-ignitive characteristics. The temperature of the gas and air just prior to admixture also materially modifies the speed of explosive propagation, increase of initial temperature having an accelerating effect. Pressure likewise exerts an influence although this is relatively slight under ordinary furnace conditions where the pressure is usually nearly atmospheric. However with considerably increased pressure or operation of a furnace under the suction principle this factor must be given some consideration. Another factor is the permeability of the porous mass on which, at constant pressure, the rate of travel of the agents of combustion also depends.

In applying the process of the present invention to, for example, a muffle furnace or gas retort furnace, the space between the walls of the furnace and the muffle is largely filled with fragments of granular refractory material of a size in part depending on the size of the muffle chamber, but ranging usually from one inch to three inches in diameter. A regenerator or recuperator is provided to permit of preheating the air, and gas also if desired. The gas and air are introduced into the combustion chamber through ports which closely approximate but whose spacing depends upon the character and temperature of the incoming agents of combustion, so that the loci of confluence, within the porosities of the mass of granular material, may be predetermined and the regulation and control of surface combustion with preheated gases secured. The ports for the entry of the gas and air may be situated at or near the top of the

furnace structure so that the top of the muffle receives the maximum heat, causing the material in the muffle, whether mineral matter, coal and the like, to be exposed to a very high degree of radiant heat. The exit ports in such a case may be at or near the bottom of the furnace. With vertical retorts, the position of the parts may be adjusted to correspond to a furnace shaped therefor.

10 The drawing shows in cross sectional view a muffle furnace adapted for carrying out the process of the present invention.

Referring to the drawing, in the furnace shown the space between the walls of the muffle 10 and the outer furnace walls 11 is filled with a mass of granular refractory material 12. This granular material forms the porous and permeable combustion bed which, as shown, completely surrounds the muffle. The combustible gas and air are injected into the combustion bed through inlet pipes or nozzles 13 and 14 arranged in one or more pairs, each pair including a gas inlet and an air inlet set comparatively close together and relatively adjustable to vary the space between them as may be required according to the character and temperature of the incoming agents of combustion. As shown, two such pairs of gas and air supply nozzles are provided arranged for injecting the gas and air through the top of the furnace into the upper part of the combustion bed and an exit port is provided in the bottom wall of the furnace to permit the products of combustion to pass out through a discharge pipe 15. The gas and air may be supplied under suitable pressure from any suitable source or by suitable means such as the pumps 16 and 17 respectively, as shown, the gas passing from the pump 16 through pipe 18 to the nozzles 13, and the air passing from the pump 17 through pipe 19 to the nozzles 14. For adjusting the spacing of the nozzles of each pair in the construction shown the air nozzles are carried by a section of pipe which has a sleeve-connection with the main portion of the pipe 19 and is adjustable as by means of a screw 20 to move the nozzles 14 toward or from the gas nozzles 13, suitable slide plates 21 being provided to close the opening in the furnace wall through which the nozzles extend. For pre-heating the air supplied to the nozzles 14, the pipe 19 leading from the air pump passes through a chamber 22 through which pass the products of combustion from the discharge pipe 15. If it is desired to pre-heat the combustible gas as well as the air, the gas supply pipe 18 may also be passed through the heating chamber 22 for a greater or less distance as may be found desirable. The supply of gas and air may be controlled by suitably regulating the pumps or by means of valves 25 and 26 arranged respec-

tively in the gas and air supply pipes 18 and 19. The streams or currents of gas and air entering the combustion bed from each pair of nozzles will gradually commingle and the bed being highly heated when the furnace is in operation combustion will take place adjacent the highly heated surfaces of the material of the bed at the points or places where intimate mixture or confluence of the gas and air takes place.

75

What I claim is:—

1. The process of producing heat which comprises injecting into a highly heated porous and permeable bed of refractory material currents of gas and air to commingle within the bed and to cause combustion to take place adjacent the highly heated interior surfaces of the bed at the points of confluence of the gas and air, and positioning the points or places of confluence of the gas and air with respect to the preignitive characteristics of the gas and the respective temperatures of the gas and air.

80

2. The process of producing heat which comprises injecting into a highly heated porous and permeable bed of refractory material a current of a combustible gas and a current of a supporter of combustion to commingle within the bed and to cause combustion to take place adjacent the highly heated interior surfaces of the bed at the points of confluence of the gas and the combustion supporter, and positioning the points or places of confluence of the gas and combustion supporter with respect to their 95 respective initial temperatures.

90

3. The process of producing heat which comprises injecting into a highly heated porous and permeable bed of refractory material a current of a combustible gas and a current of a supporter of combustion to commingle within the bed and to cause combustion to take place adjacent the highly heated interior surfaces of the bed at the points of confluence of the gas and the combustion supporter, and positioning the points or places of confluence of the gas and combustion supporter with respect to their 100 chemical characteristics.

105

4. The process of producing heat which comprises injecting into a highly heated porous and permeable bed of refractory material a current of hot gaseous combustible and an adjacent current of preheated air to commingle within the bed and to cause combustion to take place adjacent the highly heated interior surfaces of the bed at the points of confluence of the combustible and air.

110

5. The process of producing heat which comprises injecting into a highly heated porous and permeable bed of refractory material a current of gaseous combustible and a current of preheated air to commingle within the bed and to cause combustion to 125

120

130

take place adjacent the highly heated surfaces of the bed at the points of confluence of the gas and air.

6. The process of producing heat which comprises injecting into a highly heated porous and permeable bed of refractory material a current of combustible gas and a current of regeneratively heated air to commingle within the bed and to cause combustion to take place adjacent the highly heated interior surfaces of the bed at the points of confluence of the gas and air, and positioning the points or places of confluence of the gas and air with respect to the preignited characteristics of the gas, the temperature of the air and the permeability of the bed.

7. The process of producing heat which comprises injecting into a highly heated porous and permeable bed of refractory material a current of combustible gas and a current of air to commingle within the bed and to cause combustion to take place adjacent the highly heated interior surfaces of the bed at the points of confluence of the gas and air, withdrawing the hot products of

combustion, and regeneratively transferring a portion of the heat of the products of combustion to at least one of the entering agents of combustion.

8. The process of producing heat which comprises injecting into a highly heated porous and permeable bed of refractory material a current of combustible gas and a current of air to commingle within the bed and to cause combustion to take place adjacent the highly heated interior surfaces of the bed at the points of confluence of the gas and air, withdrawing the hot products of combustion, and preheating the entering gas and air by transferring thereto a portion of the heat of the withdrawn products of combustion.

Signed at Montclair, in the county of Essex and State of New Jersey, this 5th day of December, A. D. 1911.

CARLETON ELLIS.
